Patented Mar. 16, 1976

239,168

VEHICLE WIND DEFLECTOR

Donald G. Hart, R.R. 1, Geneseo, Ill. 61254

Filed Dec. 7, 1973, Ser. No. 422,658

Term of patent 14 years

Int. Cl. D12—16

U.S. Cl. D12—181

FIG. 1

FIG. 2

FIG. 3

FIG. 4

FIG. 5

FIG. 1 is a front elevational view of a vehicle wind deflector showing my new design;

FIG. 2 is a top plan view thereof;

FIG. 3 is an end elevational view thereof, with the opposite end being a mirror image thereof;

FIG. 4 is a rear elevational view thereof; and

FIG. 5 is a bottom plan view thereof.

I claim:

The ornamental design of a vehicle wind deflector, substantially as shown.
